UNITED STATES PATENT OFFICE.

MACK M. SWAIN, OF LOS ANGELES, CALIFORNIA.

ACCELERATOR-PEDAL-OPERATING UNIT.

Application filed March 13, 1926. Serial No. 94,495.

This invention relates to improvements in foot rest and pedal extensions for operating the accelerators of motor vehicles.

The primary object of this invention is the provision of a relatively simple and efficient type of foot rest which may be adjusted to comfortably receive the foot of an operator for operating an accelerator, and which may be extended upwardly and to the rear for the purpose of comfortably receiving the foot of a short legged person, whereby an accelerator pedal may be operated conveniently and without straining.

A further object of this invention is the provision of an accelerator pedal extension unit embodying a comfortable foot rest which may be collapsed into an operating relation with an accelerator pedal, for operation by long-legged persons with the foot supported in a comfortable position, or which may be extended upwardly and to the rear for comfortably receiving the foot of shorter-legged persons in order that the accelerator pedal may be conveniently operated with ease; the adjustment from one position to another being capable of manipulation without detachment or alteration of parts.

Other objects and advantages of this invention will be apparent during the course of the following detailed description.

In the accompanying drawing, forming a part of this specification, and wherein similar reference characters designate corresponding parts throughout the several views,

Figure 1 is a perspective view of the improved foot rest and pedal extension unit showing the same attached on the floor boards of a conventional automotive vehicle for operating an ordinary accelerator pedal; the improved unit being shown extended in this figure for operation by short-legged persons.

Figure 2 is a longitudinal sectional view taken through the improved foot rest and pedal extension unit, showing the same collapsed into a pedal operating relation for comfortably receiving the foot of long-legged persons.

Figure 3 is a fragmentary sectional view taken through the rear end of the improved unit, with the rear end parts in the position they will assume when adapted for operation by short-legged persons.

Figure 4 is a sectional view taken substantially on the line 4-4 of Figure 3.

Figure 5 is a sectional view taken transversely through the forward part of the improved unit, when extended for operation by short-legged persons.

Figure 6 is a cross sectional view taken substantially on the line 6-6 of Figure 2.

Figure 7 is a bottom plan view of the foot plate portion of the invention, showing more particularly the means by which a resilient mat is assembled thereon.

In the drawing, wherein for the purpose of illustration is shown only a preferred embodiment of this invention, the letter A may generally designate the improved unit, which is adapted for placement upon a support B, such as the floor boards of a vehicle, in a convenient position for operation of the accelerator pedal C.

The improved unit A preferably comprises an attaching portion D adapted for connection in a rigid manner upon the support B. An accelerating pedal contact and operating lever arm E is pivotally connected to the support or base D, and supports a foot rest plate F thereon by collapsible means G. The foot rest plate F may receive thereon a resilient or flexible foot contact pad H formed in a novel relation for receiving the feet of long and short-legged persons in a comfortable relation.

The base D is preferably of cast metal, or any approved material, and it includes the socket or hollow body 10, which at the lower end thereof is provided with an outwardly extending attaching flange 11 provided with openings 12 therethrough for receiving screws 13 or the like by means of which the base D may be attached to the toe board or floor board B of the vehicle. The socket or body 10 includes a rear wall 14; side walls 15; and is recessed at the front at 17 to provide a short front wall 16 which extends from the base flange 11 upwardly and terminates below the top edges of the walls 14 and 15, to permit the operating movement of the pedal operating lever E. The portion 10 thus provides a socket compartment 18 therein across which a transverse supporting pin 19 extends; the ends thereof being supported in the side walls 15, somewhat after the manner illustrated in Figure 4 of the drawing, and the screw threaded end of the pin 19 may be peened over to prevent detachment of the pin or pintle 19.

The operating lever E is elongated, and

the same may be made of cast aluminum or any approved material. It includes the long body portion 20, which at the rear end thereof is enlarged at 21 and transversely apertured for receiving the pintle 19 therethrough whereby to pivotally mount its end 21 of the lever E in the socket or body 10 of the base D with the same forwardly extending thru the recess 17 above the front wall 16. The forward end 24 of the body 10 is wider than the remaining portion, and adapted for resting directly on top of the accelerator pedal C. This portion 24 is preferably provided with the spaced parallel upwardly extending integral lugs or bracket extensions 25, transversely apertured in aligning relation for receiving a detachable pin 26, upon which the lower end of a connecting link 27 is mounted; the connecting link 27 being part of the means G which will be subsequently described in its relation to other details of the invention.

The lever E also includes a right angled stop extension 30 at the rear end thereof, which faces downwardly in the socket compartment 18, and is adapted to abut against the inner end of an adjustable stop screw or member 31 which is adjustably carried by the front wall 16 of the base D. This stop member 31 regulates the upward amplitude of movement of the lever E, and is very important to prevent any loose play between the end 24 of the lever E and the operating pedal C, when the latter is fully extended and the carburetor is closed. Thus, the forward end of the lever E may always be maintained in contact with the pedal C, for operation of the latter, and the upward tipping of the lever E cannot be occasioned so as to space the same at its free end from the pedal C when the latter is fully extended when the carburetor is closed for feeding fuel.

The means G comprises the front link 27 which collapsibly connects the lever E with the foot plate F, and the collapsible and extensible rear link construction 35 which connects the base D and the foot plate F for extended or collapsed positioning of the latter.

The foot plate F is preferably of rigid construction, and is of metal. It is preferably of uniform width through the major length thereof, but may be rounded at its rear edge 37 as illustrated in Figure 7 of the drawing, and at its front end the same is tapered by converging the edges 38 to a blunt point or edge 39. On the lower surface thereof the plate F is provided with a front pair of apertured lugs or brackets 40 which detachably receive thereacross a pin or pintle 41 upon which the upper end of the link 27 pivots. The link 27 as illustrated in Figure 5 of the drawing is apertured at its upper end for receiving the said pin 41, and

at its lower end it is likewise apertured as above mentioned for receiving the pin 26. The link 27 permits the plate F to be pushed forwardly and collapsed down immediately over the lever E, or permits the foot plate F to be elevated into a spaced relation above the lever E, with the link 27 arranged in substantially right angled relation between the plate F and lever E, as illustrated in Figure 1 of the drawing.

The link 35 includes a body portion 36, having an upwardly extending reduced shank 37, which is rolled at its upper end 38 to provide a transverse passageway to pivot upon a pin 44; the pin 44 being supported in a detachable relation by means of spaced parallel apertured lugs 46 which are connected integral with the foot plate F and depend from the bottom surface thereof at the rear end of the same. The link 35 furthermore includes the spaced parallel legs 48 and 49, which are hooked as at 50, at the lower ends thereof, and which slidably extend into the socket compartment 18 of the base D, at opposite sides of the lever end 21 and extension 30, as is illustrated in Figure 4 of the drawings. The hooked ends 50 of the legs 48 and 49 are open, and the link 35 may be reciprocated back and forth in the socket compartment 18 to place the hooked ends 50 downwardly into the socket compartment to vertically position the link 35 in a stable braced relation, or the link 35 may be pulled upwardly, to move the hooks 50 above the top edge of the wall 17, into engagement with the pin 19, and from which position the link 35 may be moved forwardly upon collapsing of the foot plate F, as is illustrated in Figure 2 of the drawing. The fact that the hooked ends 50 open upwardly prevent detachment of the link 35 from the base D, as said hooks 50 will engage the pin 19 to prevent disconnection of the link. The hooked ends 50 of the link 35 are of about the same width as the width of the compartment 18, or slightly greater, and in order to fit snugly in the compartment 18 between the front and rear walls 14 and 16 thereof, as is illustrated in Figure 3 of the drawing, to brace the link in a stable extended relation.

The link 35 has a resilient clamp 60 connected therewith, including outwardly extending resilient fingers 61 which may flex to engage the portion 20 of the lever E when the link 35 is collapsed upon the lever E, as illustrated in Figure 2 of the drawing, in order to hold the foot plate F collapsed upon the lever portion E, as illustrated in Figures 2 and 6 of the drawing.

From so much of the description of the unit as above given, it is apparent that when the base D is connected upon the floor board B, the lever E at its forward end rests upon the accelerator pedal C. If a short-legged

person is to operate the pedal C, it is merely necessary to pull the foot plate F upwardly from the lever E, and the clamp fingers 61 will release their hold upon the lever body 20, due to the exerted force, and the links 27 and 35 will pivot at their lower ends and move upwardly, to permit the movement of the foot plate F upwardly into a spaced relation over the lever E. When the foot plate F has been elevated to the desired extent, and the link 35 is extended, the link 35 in its extended position is then pushed downwardly into the socket compartment 18 as far as it will go, by gently pressing upon the rear end of the foot plate F, and the hook ends 50 of the link 35 will then engage into a stable braced relation in the socket compartment 18 of the base D, in order to position the foot plate F in a supported spaced relation, extended over the lever E, and the links 27 and 35 cannot be collapsed so long as the link 35 has the hooked portions of the legs 48 and 49 thereof extended downwardly into the socket compartment 18 between the front and rear walls of the base D, as illustrated in Figures 3 and 4 of the drawing.

If a long-legged person is to operate the accelerator pedal, it is merely necessary to pull upwardly at the rear end of the foot plate F, when the unit is in the extended position as illustrated in Figure 1 of the drawing, and this pulls the link 35 upwardly from its socket engagement in the base D, and permits the forward and downward collapsing of the foot plate F into the closely spaced relation over the lever E. In this position the resilient fingers 61 engage the lever body 20 and lock the parts of the unit A in a collapsed relation to permit of operation of the accelerator pedal by long-legged persons.

It is preferred to place the mat or foot pad H upon the foot plate F, and to this end the same is preferably formed of some flexible or resilient material, such as rubber. It may be moulded to form, and is readily detachable from the foot plate F. In the preferred construction thereof the same is elongated in substantially the form of the sole and heel of a foot, and it comprises a body portion 70, which on the lower surface thereof is provided with lateral flanges 71 and 72, and a rear flange 73, formed along the major length at the sides thereof, and at the rear end, to provide a substantially U-shaped groove 75 in which the marginal portions of the foot plate F may be received. The flanges 71 and 72 extend to a point short of the toe end of the foot pedal mat H, approximately in the vicinity of the link 27, and from this point forwardly the flanges are not provided, so that the toe portion 77 of the body 70 of the mat H may be lifted upwardly from the front end

of the foot plate F. A retaining lug 78 is formed on the bottom surface of the toe portion 77 of the mat H, adapted for abutment against the front edge 39 of the foot plate F, to prevent the sliding of the mat H rearwardly from its pocketed connection with the foot plate F, when the latter is received in the groove 75. The groove 75 in lieu of the formation above described may be termed a pocket. 75

The top surface of the body 70 is formed in a novel manner. It includes a heel portion 80 adapted to receive the heel of shoes of persons having large feet, and at the front of the heel portion 80 a transverse retaining strip or rib 81 extends across the body 70, and immediately forwardly of this strip 81 is formed a heel socket 82 adapted to receive the heels of ladies' shoes or the shoes of persons having small feet. 85

From the foregoing description of this invention it is apparent that a novel foot rest and accelerator pedal extension unit has been provided, which is capable of being stably supported in an upper extended rearwardly positioned manner, or which may be collapsed downwardly and slightly forwardly in order to accommodate the feet of persons having long and short legs. 90

Various changes in the shape, size, and arrangement of parts may be made to the form of invention herein shown and described, without departing from the spirit of this invention or the scope of the claims. 95

I claim:

1. In an accelerator pedal operating unit the combination of a floor attaching base, a foot supporting member, means pivotally and adjustably connecting said foot supporting member to said base, a pedal operating lever pivotally connected to said base, and means connecting said lever at its outer end to an outer end of said foot supporting member to permit collapsing or extension of the foot supporting member with respect to 110 the lever.

2. In an accelerator pedal operating unit the combination of a base, a foot rest member, means adjustably connecting the foot rest member to the base, an elongated accelerator pedal contact lever pivotally connected to the base extending forwardly therefrom, and collapsible link means pivotally connecting the forward end of the lever with the forward end of said foot rest member. 120

3. In an accelerator pedal operating unit the combination of a base having a socket opening therein, a foot rest member, a link pivotally connected at the rear end to said foot rest member, and means for pivotally connecting the link to said base for collapsed positioning of the foot rest member with respect to the base, and permitting the link to be extended into the socket of the base for stably supporting the same in an 125 130

upwardly extending relation from the base for supporting the foot rest member in any extended relation with respect to the base.

4. In an accelerator pedal operating unit 5 the combination of a supporting base having a socket opening therein, a foot rest member, and a link movably connected with said foot rest member adapted to be detachably positioned in the socket of the base for sup- 10 porting the link in a stable extended relation with respect to the base.

5. In an accelerator pedal operating unit 15 the combination of a supporting base having a socket opening therein, a foot rest member, a link movably connected with said foot rest member adapted to be detachably positioned in the socket of the base for supporting the link in a stable extended relation with respect to the base; and means 20 carried by the base to prevent disconnection of the link from the base and to permit the pivoted movement of the link on the base when it is removed from said socket whereby to collapse the foot rest member 25 with respect to the base.

6. In an accelerator pedal operating unit the combination of a base, an operating lever movably connected with the base ex-

tending forwardly therefrom, a foot rest member, collapsible link means pivotally 30 connecting the forward ends of the foot rest member and lever, and collapsible means for rearwardly connecting the rear end of the foot rest member and base.

7. In an accelerator pedal operating unit 35 the combination of an attaching base having a socket opening therein, a pin supported by the base extending transversely across the socket opening, a forwardly ex- 40 tending lever pivotally connected to said pin, a foot rest member, a link pivotally connected to the foot rest member at the rear end thereof, said link having a lower end adapted to be received in the socket of the base to stably support the link in an up- 45 wardly extending relation from the base, said link having a hooked end adapted to engage over the pin of the base when the link is removed from the socket opening to permit the collapsing of the foot rest member with respect to the lever; and a connecting link pivotally connected at its ends to the forward ends of said lever and foot rest member.

MACK M. SWAIN.
